UNITED STATES PATENT OFFICE.

ATEN BOWMAN HOWER AND SERRIN JEROME FINCH, OF OSTRANDER, OHIO.

DESIGN FOR A PHOTOGRAPHIC MOUNT.

SPECIFICATION forming part of Design No. 34,877, dated July 30, 1901.

Application filed June 29, 1901. Serial No. 66,615. Term of patent 3½ years.

To all whom it may concern:

Be it known that we, ATEN BOWMAN HOWER and SERRIN JEROME FINCH, citizens of the United States, residing at Ostrander, in the county of Delaware and State of Ohio, have invented and produced a new and original Design for a Photographic Mount, of which the following is a specification.

The present invention relates to designs for photographic mounts; and the object thereof is to provide a design of this character that is original, novel, and ornamental.

The leading feature of the design resides in an elliptical or oval card mount or plate having the representation of the figure of a buffalo located longitudinally upon one face of the same and arranging in the center of the card a circular flat picture-receiving space or opening that cuts out a portion of the center of the figure of the buffalo.

Minor features of the design reside in representing the buffalo as standing upon a level foreground and in depicting the background as hilly or mountainous.

In the drawings, Figure 1 is a side elevation of a photographic mount embodying the

present design. Fig. 2 is an end elevation of the same.

The card is designated in the drawings by the reference-numeral 1, and the figure of a ³⁰ buffalo, located longitudinally upon the same, by the reference-numeral 2. A circular space or opening 3 is arranged in the center of the card and cuts out the central portion of the figure of the buffalo. The foreground upon ³⁵ which the buffalo stands is designated 4 and is practically level, while the background 5 is represented hilly or mountainous.

Having thus described the invention, what we claim as new, and desire to secure by Letters Patent, is—

The design for a photographic mount, as herein shown and described.

In testimony that we claim the foregoing as our own we have hereto affixed our signatures ⁴⁵ in the presence of two witnesses.
